UNITED STATES PATENT OFFICE.

CHESLEY T. SMALL, OF ST. LOUIS, MISSOURI.

HOPPER FOR FILLING MACHINES.

Application filed January 3, 1928. Serial No. 244,218.

My invention relates to hoppers for supplying powdered material to can filling machines or the like, and particularly to such hoppers of large size holding a great quantity of material. I have found that in such hoppers the weight of the material causes it to become tightly packed in the lower part of the hopper so that when it is loosened by the agitators and passes out through the discharge nozzle the bulk of the material will be maintained in position by the packed powder until a considerable cavity is formed around the agitators. After a time the entire mass will drop owing to the breaking down of the roof of the cavity by the weight of the material. This is not only injurious to the hopper but also causes irregularity of the filling machine supplied by the hopper. It is the object of my invention to provide a hopper in which the material will be fed uniformly without the formation of cavities therein and the consequent dropping en masse of material therein.

In the accompanying drawings, which illustrate one form of hopper made in accordance with my invention, Figure 1 is a vertical section; Figure 2 is an enlarged section through the upper end of one of the vent pipes; and Figure 3 is an enlarged section of one of the bearing boxes.

The hopper which, in the drawings is shown as suspended from a ceiling 1, is composed of an upper cylindrical part 2 and a lower conical part 3 terminating in a discharge nozzle 4. I have found that the angle of the walls of the conical part 3 is of importance in securing the desired results and that an angle of 30 degrees from the perpendicular is more effective than a larger or smaller angle. The nozzle is provided with a cut-off plate 5 and has passing through it an agitator shaft 6 journaled in brackets 7 secured to the conical part of the hopper. Secured to one end of shaft 6 is a driving pulley 8 and to the other a gear wheel 9. Meshing with the gear 9 is a gear 10 mounted on an agitator shaft 11 passing through the hopper just above the nozzle and journaled in the bracket 7. Wheel 9 is smaller than wheel 10 so that shaft 11 will be driven at a somewhat slower rate of speed than shaft 6. On the shaft 11 is a second gear wheel 12 meshing with a gear wheel 13 on an agitator shaft 14 passing through the hopper above the shaft 11. Wheel 12 is smaller than wheel 13 so that

shaft 14 will be driven at a still slower speed than shaft 11. Shaft 14 is journaled in brackets 7 and preferably also has the end adjacent to wheel 13 supported by an auxiliary bearing carried by arm 15 depending from one of said brackets. The other bracket is also provided with a similar arm so that the gearing may be placed at the opposite side of the hopper when so desired. In order to prevent escape of powder around the shaft 14 I make the bearing boxes 24 follow, as shown in Figure 3, and provide it, at its upper side, with an opening 25 through which packing material 26, such as cotton waste may be introduced. The shafts 11 and 6 are also preferably provided with similar packed bearings 27 and 28, respectively.

Powder is introduced into the hopper through opening 16 in the ceiling 1. Adjacent to the sides of this opening are a pair 75 of hangers 17 carrying a supporting bar 18 on which vent pipes 19 are mounted so that their lower ends, which terminate adjacent to the agitator shaft 14, will be free to swing. This swinging mounting is preferably secured by passing the shaft 18 through holes 20 (Figure 2) in the walls of the pipes 19 adjacent to the upper ends. In order to prevent the entrance of the powder into the upper ends of the vent pipes and the consequent 85 choking when the hopper is filled, I provide the pipes with caps 21 preferably conical in form. These caps are carried by collars 22 sliding on the pipes and so are readily removable to give access to the interior of the pipes 90 for cleaning. Notches 23 formed in the upper ends of the pipes provide free passage of air into or out of the pipes.

By the use of the proper inclination of the side of the hopper, together with agitators 95 increasing in speed toward the lower end of the hopper and vent pipes free to swing in the hopper adjacent to the agitator shaft, I overcome the formation of cavities in the material in the hopper and secure even and uniform feed of the material in the largest hoppers.

Having fully described my invention, what I claim as new and desire to secure by Letters Patent of the United States is:

1. In a device of the class described, the combination with a hopper, of an agitator in the lower part of said hopper, and a swinging vent pipe in said hopper terminating adjacent to said agitator.

2. In a device of the class described, the combination with a hopper, of an agitator shaft extending horizontally through the lower part of said hopper, and a plurality of vent pipes in said hopper terminating adjacent to said agitator shaft, the lower ends of said pipes being free to swing under the influence of the moving powder.
3. In a device of the class described, the combination with a hopper having inclined walls at the lower end, of an agitator shaft extending horizontally through the lower end of said hopper, and a vent pipe in said hopper terminating adjacent to said agitator shaft, said vent pipe being free to swing under the influence of the moving powder.
4. In a device of the class described, the combination with a hopper having inclined walls at the lower end, of an agitator shaft extending horizontally through the lower end of said hopper, a second agitator shaft below said first named shaft and driven at a greater speed than said first named shaft, and a vent pipe in said hopper terminating adjacent to said first named shaft, said pipe being free to swing under the influence of the moving powder.
5. In a device of the class described, the combination with a hopper having the opposing walls of its lower end each inclined at an angle of substantially 30 degrees from the perpendicular, of an agitator shaft extending horizontally through the lower part of said hopper, and a second agitator shaft below said first named shaft and driven at a greater speed than said first named shaft.
6. In a device of the class described, the combination with a hopper having the opposing walls of its lower end each inclined at an angle of substantially 30 degrees from the perpendicular, of an agitator shaft extending horizontally through the lower part of said hopper, and a vent pipe in said hopper terminating adjacent to said shaft, said pipe being free to swing under the influence of the moving powder.
7. In a device of the class described, the combination with a hopper having the walls of its lower end inclined at an angle of substantially 30 degrees from the perpendicular, of an agitator shaft extending horizontally through the lower part of said hopper, a second agitator shaft below said first named shaft and driven at a greater speed than said first named shaft, and a plurality of vent pipes in said hopper terminating adjacent to said first named shaft, said pipes being free to swing under the influence of the moving powder.

In testimony whereof, I hereunto affix my signature, this 29th day of December, 1927.

CHESLEY T. SMALL.
